Primary Examiner — Karen E Eldridge Powers(74) *Attorney, Agent, or Firm* — Hahn Loeser & Parks LLP(57) **CLAIM**

The ornamental design for a welder's glove, as shown and described.

DESCRIPTION

FIG. 1 is a perspective view of a first embodiment of a welder's glove.

FIG. 2 is a front elevational view thereof;

FIG. 3 is a rear elevational view thereof;

FIG. 4 is a left-side view thereof;

FIG. 5 is a right-side view thereof;

FIG. 6 is a top elevational view thereof; and,

FIG. 7 is a bottom elevational view thereof.

The broken lines shown in the drawings illustrate features of the article in which the design is embodied that form no part of the claim.
